UNITED STATES PATENT OFFICE

148,118

DESIGN FOR A MATCH BOOK HOLDER

John H. Sutton, Los Angeles, Calif.

Application September 17, 1946, Serial No. 133,374

Term of patent 14 years

(Cl. D48—29)

To all whom it may concern:

Be it known that I, John H. Sutton, a citizen of Canada, residing at Los Angeles, in the county of Los Angeles and State of California, have invented a new, original, and ornamental Design for a Match Book Holder, of which the following is a specification, reference being had to the accompanying drawing, forming a part thereof.

I claim:

The ornamental design for a match book holder, as shown.

JOHN H. SUTTON.
